UNITED STATES PATENT OFFICE

GEORGE S. HILTZ, OF BROOKLYN, NEW YORK, ASSIGNOR TO STOCK QUOTATION TELEGRAPH COMPANY, OF NEW YORK, N. Y., A CORPORATION OF NEW YORK

PRINTING TELEGRAPH

Application filed November 28, 1927. Serial No. 236,084.

This invention relates to an improvement in printing telegraphs and particularly to that type of apparatus in which the type wheel or type carrying apparatus is caused to be actuated in a step-by-step manner by current impulses sent over the line wire.

In such apparatus, a number of receivers are on the one line and are all controlled by a single manually operated transmitting machine. In the operation of such machines, the transmitter is operated through a keyboard, the operation of the keys of this board effecting certain electrical conditions in the circuits of the receivers to cause the desired impressions to be made on a recording tape or other suitable type of record.

It is one of the objects of this invention to provide a printing telegraph apparatus of such a character that the receiving machine may be readily brought to unison with the transmitting apparatus. Heretofore, difficulty has been experienced with the receivers becoming out of unison so as not to print correctly the matter sent out by the transmitter, and to avoid this difficulty the operator of the transmitting machine is required at intervals to operate a certain key on the keyboard to bring all of the machines on that line in unison. The difficulty with such an arrangement is, however, that the operator in the rush of a busy market may neglect to operate this key and the result is that any machine on the line which is not in unison will continue in that condition until the operator chances to again operate the unison key.

By the present arrangement, however, I have provided an arrangement for bringing the machines into unison with the transmitter by the operation of the period key on the keyboard, selecting the period key deliberately for the reason that in telegraph printers it is the universal custom to employ the period key as the spacer and consequently this key is bound to be operated at very frequent intervals. It is to be understood, however, that any other keys on the keyboard can be selected if so desired.

In general, my invention consists in interposing a stop in the path of the type carrying apparatus whereby when the period key

on the transmitting machine is operated, this stop mechanism will be moved to type-stopping position and will remain in this position until the receiver is brought to unison, at which time the receiving machine will automatically resume its normal operation in unison with the transmitter.

In the accompanying drawings wherein I have illustrated one embodiment of my invention,

Fig. 1 shows more or less diagrammatically, and in side elevation, a telegraph printing machine of the receiving type with my invention applied thereto,

Fig. 2 is an end elevation of the machine of Fig. 1 looking at the machine from the front thereof with parts removed so as to show the details of the unisoning mechanism;

Fig. 3 is a plan view of the showing of Fig. 2;

Figs. 4, 5 and 6 are detail views of the stop mechanism in various positions which the same may take during the operation of the machine, Fig. 4 being a section on the line 4-4 of Fig. 3; and

Fig. 7 is a wiring diagram.

Referring first of all to Figs. 1 to 6 inclusive, the receiving machine comprises a type wheel shaft or carrier 1, carrying type wheels 2 and 3 as is usual. The type shaft 1 is provided with escapement mechanism comprising a cooperating scape wheel and escapement pawl 5. The pawl 5 is vibrated by means of escapement magnets 6 and 7, the operation of which will be described in detail hereinafter, 80 these magnets, however, being provided with a common armature 8, which is attached, as illustrated, directly to the escapement pawl 5.

Rigidly secured to the type shaft 1 is a stop pin 4, this pin being provided on the underside, as viewed in Fig. 1, with a shoulder 4'.

Below the escapement magnets 6 and 7 is a unison or unisoning magnet 10, the armature of which is designated 11, and is secured to a short shaft 12 extending transversely of the machine. The shaft 12 also has secured to it, a short arm 13 to the outer end of which is attached a spring 14 anchored at 15 to a convenient part of the frame of the machine. The

function of the spring 14 is to retain the armature 11 in the position shown in Fig. 1 when the electromagnet 10 is not energized.

The shaft 12 projects through the frame 5 of the machine as shown in Fig. 2, and has attached to its outer end, an arm 16 this unisoning arm extending upwardly vertically of the machine frame to a point adjacent the end of the stop pin 4 on the type shaft 1 heretofore 10 referred to.

The upper end of the unisoning arm 16 is laterally extended to provide a portion 17 extending toward the escapement mechanism, this lateral extension 17 having pivoted thereon 15 a unison stop lever 18 lying between the lateral extension 17 and the type shaft 1. The extreme inner end of the lateral extension 17 is provided with an adjustable stop 19 for limiting the movement in one direction of the 20 unison stop lever 18. The stop lever 18 pivots at 20 and is frictionally held in adjusted position.

The type shaft 1 carries a disc 21 which rotates with the shaft and under certain conditions, as will be hereinafter explained, is adapted to be engaged by the member 18. This disc 21 is provided in its periphery with a notch 22 so proportioned and so located as to permit the end of the member 18 to swing 30 thereinto under certain conditions, as will be hereinafter explained.

Referring now to the wiring diagram of Fig. 7, 23 designates the keyboard of the transmitting machine on which, for purposes 35 of illustration, I have shown only two keys, to wit, 24 and 25. The key 25 in this instance is assumed to be the period or spacer key, although, as I have mentioned above, this is not essential to the operation of my invention. 40 26 designates the sunflower or stationary commutator of the transmitter. This construction is not new with me and hence will not be described in detail except to say that the shaft 27 thereof, carries a trailer or rotary 45 contact 28, the trailing end of which is adapted to make contact successively with the contact segments 29 of the sunflower. Geared to the shaft 27 in the usual way is a clutch shaft and a clutch magnet 30, this shaft being provided 50 with an insulating strip 31 adapted to be engaged alternately by brushes 32 and 33. 34 designates a brush which is in constant contact with the clutch shaft.

As is usual in machines of this character, 55 the escapement mechanism is operated by change in polarity of the line current, the escapement magnets 6 and 7 being specially wound for this purpose, so that the magnet 6 on one polarity will attract the armature 8 in one direction and on a change in polarity, the magnet 7 will attract this armature in the opposite direction thereby effecting the desired vibration of the escapement member 5 and permitting an intermittent rotation 60 always in the one direction of the scape wheel.

Change in polarity is effected by polar relay P R in conjunction with brushes 32 and 33.

Coming now to the operation of my improved mechanism, it being understood, of course, that the shaft 27 and the clutch shaft are rotating, operation of the key 24 will close a circuit to the clutch relay 35 as follows:—from the plus side of the line conductor 36, ring 37 contact made by operation of the key 24, conductor 38, commutator or sunflower segment 39, trailer 28, when the trailing end thereof reaches this segment, brush 40, conductor 41, clutch relay 35 to ground 42.

The operation of the clutch relay effects a closing of the circuit for the clutch magnet 30 from the plus or positive side of the line, by way of conductor 43, armature 44 of the clutch relay, fixed contact 45, conductor 46, clutch magnet 30 and ground 47. The transmitter shaft by the operation of the clutch magnet 30 now will be held stationary and the impress magnet 49 will effect proper impression of the character, corresponding to the key 24, upon the tape or other record. It will be noticed that the unison magnet 10 above referred to is in series with the escapement magnets 6 and 7, and the impress magnet 49. However, the magnet 10 is so wound as not to function on the comparatively light current employed in the operation so far described.

Assuming now that the receiver is out of unison with the transmitter, in other words, assuming that the characters being recorded by the receiver do not correspond to the keys operated on the keyboard, unison conditions can be restored by operation of the spacer or period key 25.

The spacer key 25 has been selected for this purpose as it is necessarily frequently operated in the operation of the transmitter. When the period or spacer key 25 is operated, a circuit will be established for an electromagnetic switch 50 which may be traced as follows: from the plus side of the line by way of conductor 36, ring 23, through the contacts of the period key 25, conductor 51, winding of the magnet 50, conductor 52, sunflower segment 53, trailer 28, brush 40, conductor 41 winding of the clutch relay 35 to ground 42. The electromagnetic switch 50 will now actuate its armature 53 and the resistance 54, which, prior to this, was in series with the windings of the escapement magnets 6 and 7, impress magnet 49 and magnet 10 is shunted, and a current of relatively high amperage will flow through the magnet 10.

The magnet 10 will now actuate its armature 11, causing the arm 16 to be thrown to the right, as viewed in Fig. 1 into engagement with the disc 21, and the stop lever 18 to be moved to the position shown in Fig. 5.

The continued rotation of the type shaft 1 will finally bring the stop pin 4, carried by this shaft, into engagement with the unison stop lever 18, this lever abutting the shoulder 4'. As a consequence, therefore, 130

the type shaft 1 is held against further rotation and although the operator is still depressing keys on the keyboard and current is being sent through the machine, the type shaft will remain stationary until the machine has been brought into unison with the transmitter. The notch 22 in the disc 21 carried by the type shaft 1 lies abreast of the stop pin 4 so that the next time the period 5 or spacer key 25 is struck the machines will be in unison and the energization of the magnet 10 the second time will cause the unison stop lever 18 to move into the notch 22, so that the stop arm 4 can clear the same and 10 the type shaft 1 resume its rotation. It will be understood, of course, that if at the time the period key 25 is operated, the receiving machine should be in unison with the transmitter, the stop lever 18 will merely move 15 into the notch 22, engage the shoulder 4' on the arm 4 and hence instead of being tilted out of the way of this arm entirely, as the arm 16 is retracted by the spring 14, and 20 the shaft 1 will be allowed to continue its rotation. In other words, as long as the receiving machine is in unison with the transmitting machine, the operation of the period key 25, while it will actuate the arm 16 will 25 have no effect upon the operation of the receiving machine, the notch 22 at that time lying abreast of the member 18, the latter does 30 not swing on its pivot 20 into position to be engaged by the member 8.

35 From the foregoing it will be seen that means have been provided whereby manipulation of a key on the transmitting machine will effect unisoning of the receiving machine or machines with the transmitter.

40 It is to be understood that various modifications may be made in the construction above described within the purview of my invention.

What I claim is:

45 1. Unisoning mechanism for printing telegraph machines comprising in combination, a stop pin rigidly secured to and rotatable with the type shaft of the machine, a pivoted stop-lever adapted when the machine is out 50 of unison to be moved into the path of said stop pin to arrest the rotation of the type shaft, and means forming a part of said stop pin for restoring the stop-lever to non-stopping position when the machine has been 55 brought to unison.

2. Unisoning mechanism for printing telegraph machines comprising in combination, a stop pin attached to the type-carrier shaft, a shoulder on said pin, a stop-lever, means 60 for moving the same into position to stop the said pin when the machine is out of unison, and means cooperating with said shoulder for moving the stop lever out of stopping position when the machine has been restored to 65 unison.

3. Unisoning mechanism for printing telegraph machines comprising in combination, a disc carried by the type-carrier shaft, an arm attached to said shaft and movable therewith, a stop-lever, and an electromagnet for 70 actuating said lever into contact with said disc to effect movement of the lever into the path of said arm when the machine is out of unison.

4. Unisoning mechanism for printing telegraph machines comprising in combination, a disc carried by the type-carrier shaft, an arm attached to said shaft and extending laterally with respect thereto, a stop-lever, an electromagnet for actuating said lever into 75 contact with said disc to effect movement of the lever into the path of said arm when the machine is not in unison, said disc being provided with a notch for receiving said stop-lever when the machine is in unison to permit of movement of the stop-lever out of 80 stopping position.

5. Unisoning mechanism for printing telegraph machines comprising in combination, a stop arm for the type-carrier shaft, and a 90 stop-lever controlled from a transmitter adapted to be actuated electrically into the path of the stop arm when the machine is out of unison and to be actuated in the reverse direction from the transmitter when the machine 95 has been restored to unison.

6. Unisoning mechanism for printing telegraph machines comprising in combination, a stop arm, an electromagnet for actuating said stop arm, a stop lever carried by said arm, a stop adapted to cooperate with said stop lever to arrest the movement of the type carrier shaft, resistance normally in series with said electromagnet, and a switch operable from the transmitter for shunting said resistance to effect operation of said stop-lever and stop arm when the machine is out of unison and through the cooperation of said stop arm to effect movement of the stop-lever 100 out of operative position when the machine 110 is in unison.

7. Unisoning mechanism for printing telegraph machines comprising in combination, a unisoning magnet, an armature therefor, a stop arm attached to said armature, said 115 armature and stop arm being actuated upon an abnormal current flow through said magnet, a stop-pin carried by the type carrier shaft, and a pivoted stop-lever carried by said arm and movable therewith into the path of said stop-pin when the machine is out of 120 unison.

8. In a printing telegraph the combination of a scape wheel, an escapement pawl controlling the movement of the same, electro-magnets for vibrating said pawl, a stop attached to the shaft carrying said scape wheel, a stop-lever, a stop arm to which said lever is pivoted, and a second electro-magnet operable on an abnormal current flow for actuat- 125 130

ing said stop arm and lever, for pivoting said stop-lever into position to be engaged by said stop when the machine is out of unison.

9. In a printing telegraph the combination of escapement mechanism, electromagnets for operating said mechanism, a stop rigidly attached to the type shaft of the machine, a stop-lever, a stop arm to which said lever is pivoted, a second electromagnet for actuating said stop arm to pivot the said lever into operative position with respect to said stop when the machine is out of unison, said stop co-operating with the stop-lever when the machine is thereafter brought to unison to pivot the stop-lever out of stopping position upon the succeeding energization of the second named electromagnet.

This specification signed this 25th day of November, 1927.
